SEMAUTOMATIC LABEL-APPLYING
MACHINE

Sidney T. Carter, Worcester, Mass., assignor, by
mesne assignments, to Geo. J. Meyer Manufacturing
Co., Cudahy, Wis., a corporation of Wisconsin

Application June 9, 1950, Serial No. 167,131.

48 Claims. (Cl. 216—54)

1

This invention pertains to labeling machines of the semi-automatic type, more especially to a machine wherein the label is removed from the magazine by an adhesively-coated picker and then transferred from the picker to the article to be labeled by a pneumatic or suction-type carrier. In the patent to Sjoberg No. 2,292,093 dated August 4, 1942, there is described a machine of the semi-automatic type wherein a pneumatic transfer carrier moves back and forth in a substantially horizontal rectilinear path and receives a label from the picker at a transfer station and then carries it through a gumming zone and then to the labeling station. While the patented machine is very effective, it is somewhat complicated. The gum receptacle and associated parts are not so readily accessible as is desirable to facilitate proper cleaning, and since the gum is applied to the label after the latter has been transferred to the carrier, some time is lost in the gumming operation and thus the machine is not as rapid in operation as might be desired.

One object of the present invention is to provide a labeling machine of the semi-automatic type which operates according to a novel cycle of movement. A further object is to provide a labeling machine of semi-automatic type which is very simple in construction, comprising very few moving parts and which is rugged and capable of operating at high speed and for long periods of time without necessitating costly repairs or replacements. A further object is to provide a machine in which the lengths of the paths of movement of the operative elements are reduced to a minimum, thus contributing to rapidity of operation and reduction in power required for driving the machine. A further object is to provide a labeling machine of the semi-automatic type wherein the glue receptacle and associated parts are easily accessible and readily removable for cleaning and with a minimum of effort. A further object is to provide a machine of relatively small external dimensions and which is light in weight and thus readily movable from place to place, thus facilitating installation. Other and further objects and advantages of the invention will be pointed out in the following more detailed description and by reference to the accompanying drawings wherein

Fig. 1 is a front elevation of the machine, omitting certain parts and with certain parts broken away;

Fig. 2 is an elevation of the right-hand side of the machine with certain parts omitted; other parts shown in broken lines, and others in vertical section;

2

Fig. 3 is a plan view of the machine, certain parts being omitted;

Fig. 4 is a fragmentary vertical section in the diametrical plane of the main cam shaft of the machine;

Fig. 5 is a fragmentary side elevation, to larger scale, of the transfer carriage and its guides;

Fig. 6 is a fragmentary plan view of the parts shown in Fig. 5;

Fig. 7 is a diagrammatic side elevation of an air pump with certain parts in vertical section, and showing the valve-actuating part and its support;

Fig. 8 is a longitudinal section through the gum box and its supports, omitting other parts;

Fig. 9 is a plan view of the parts shown in Fig. 8;

Fig. 10 is a diagrammatic side elevation of the drive belt and belt tightener;

Fig. 11 is a diagrammatic side elevation, partly in vertical section, showing some of the operative instrumentalities in the relative positions which they occupy at the instant the picker is in contact with the endmost label in the magazine;

Fig. 12 is a similar view, but showing the picker below the picking level and with the carrier on its way back toward the gum supply;

Fig. 13 is a similar view showing the carrier at the rearmost point in its path of travel;

Figs. 14 to 18, inclusive, are diagrammatic views illustrating the cycle of operations of the picker and transfer carrier;

Fig. 19 is a fragmentary, diagrammatic elevation, partly in vertical section, showing the picker cam and the picker-actuating lever together with means for preventing normal operation of the picker;

Fig. 20 is a view generally similar to Fig. 19 but showing the parts in the position of normal operation;

Fig. 21 is a fragmentary, vertical section, to larger scale than Fig. 20, showing details of the mechanism for making the picker inoperative;

Fig. 22 is a fragmentary elevation, to larger scale than Fig. 19, showing the forward end portion of the picker-actuating lever;

Fig. 23 is a fragmentary, vertical section through the upper portion of the picker-supporting member showing in detail the connections whereby the picker is removably secured to the support;

Fig. 24 is a transverse section through the gum-transfer roll and its shaft;

Fig. 25 is a fragmentary elevation illustrating desirable means for holding the gum-transfer roll in place;

Fig. 26 is a fragmentary elevation, partly in vertical section, illustrating details of the means for actuating the label presser or wiper;

Fig. 27 is a fragmentary, vertical section, to larger scale than Fig. 21, showing details of the arm which guides the sliding detent dog;

Fig. 28 is a side view, to larger scale than Fig. 21, showing the forked toggle lever;

Fig. 29 is an elevation, partly in vertical section, showing the devices of Fig. 26 viewed from the left-hand side of the latter; and

Fig. 30 is a diagram illustrative of the cycle of operation of the several essential parts of the machine.

As here illustrated, the machine embodying the invention has a frame comprising the upright side members 1 and 2 which would usually be castings, the lower portions of these side frames diverging from each other to provide legs 3 and 4. As illustrated in Fig. 2, these legs are provided with wheels 5 to facilitate the transfer of the machine from place to place. However, the wheels may be omitted if preferred.

The side frame members 1 and 2 are provided with horizontal flanges 6 and 7 (Fig. 1) to which the base 8 of a drive motor 9 is bolted. This motor has the shaft 10 to which is fixed the grooved drive pulley 11.

A cam shaft 12 (Fig. 4) turns in bearings 13 and 14 provided in the frame members 1 and 2, respectively, and to this shaft there is fixed the hub 15 of a cam disk 16, the hub 15 being interposed between the bearings 13 and 14. In its left-hand face this cam disk has the cam groove 17; it has another cam groove 18 in its right-hand face; the left and right portions 19 and 20 of its peripheral surface constitute other cams, and intervening between these latter cam surfaces 19 and 20 there is an annular gear having the teeth 21. The teeth of this gear mesh with a pinion 22 on a shaft 23 (Fig. 4) parallel to the shaft 12 and which turns in bearings 24 and 25 in the frame members 1 and 2, respectively. This shaft projects outwardly beyond the frame member 1 and is provided with a pulley 26 whose rim is furnished with a V-groove for the reception of a drive belt 28 (Fig. 1) which also passes around the pulley 11 on the motor shaft, as above described. Preferably the grooved rim 27 of the pulley 26 is shaped to constitute a handwheel by means of which the machine may be operated slowly by hand, if desired. The belt 28 passes beneath an idler pulley 29 (Figs. 2 and 10) and over an idler pulley 30, the pulleys 29 and 30 being mounted to turn on stub shafts carried by a rocker 31, pivotally supported at 32 intermediate its ends. The rocker 31 has a bearing boss which receives a rotatable pin 33 having a diametrical, screw-threaded hole which receives the screw-threaded rear end of an adjusting shaft 34, the forward end of which is journaled in a bearing 35 (Fig. 2) integral with the frame member 2. A handwheel 36 (Fig. 2) is secured to the forward end of the shaft 34. By turning this handwheel, the member 31 is rocked and thus the belt 28 may be tightened or loosened. The belt is a V-type belt and the pulleys 11 and 26 have V-grooves and are preferably of the type designed to permit a change in the effective diameter of the drive pulley by adjustment of the tightness of the belt. While this type of drive is convenient and desirable, it is to be understood that in respect to the other aspects of the invention, the particular form of drive is immaterial.

The shaft 12 (Fig. 4) extends to the right of

the frame member 2 and on this extension of the shaft 12 there is fixed the hub 37 of a sprocket wheel 38 which drives a sprocket chain 39 (Fig. 2). This chain passes around a sprocket wheel 40 (Figs. 1, 2 and 3), turning on a stub shaft 40^a (Fig. 2) mounted on an L-shaped arm 41 having a bearing sleeve 42 at its rear end which turns on a fixed transverse shaft 54 hereafter described. A spring 43, bearing at its lower end on a bracket 44 projecting from the frame member 2, tends to swing the arm 41 in a clockwise direction (Fig. 2) and thus to tension the sprocket chain 39.

The sprocket chain 39 normally meshes with and drives a sprocket wheel 45 fixed to a shaft 46 (Figs. 2, 3, 8 and 9) which turns in bearings 47 and 48 provided in the opposite side walls of a glue box 49. This glue box is conveniently an integral casting having forwardly extending fork members 50, each having a substantially horizontal slot 51 designed to receive a fixed stud or pin 52, one of which projects inwardly from each of the frame members 1 and 2, respectively (Fig. 1). At its rear end (Fig. 8) the glue box has a rearwardly projecting arm terminating in a downwardly open hook 53 which normally hangs over the transversely extending shaft 54, above mentioned, which is mounted at its opposite ends in the frame members 1 and 2, and on one end of which the sleeves 42, above described, is mounted. The bearing members 47 and 48 preferably have forwardly directed fork members 55, each having a slot open at its front end for the reception respectively of pivoted clamping studs 56 (Figs. 3 and 9) carried by the glue box. A glue-elevating roll 57 is fixed to the shaft 46, and, as the shaft is rotated, this glue-elevating roll dips into the body of adhesive within the glue box and raises it for presentation to the roll which applies glue to the picker, as hereafter described. Preferably, a scraper blade 58 (Fig. 8) is arranged within the glue box in order to insure a coating of glue or uniform thickness on the roll 57.

This glue box is not fixed in position but is merely supported by the pins 52 and the shaft 54. By lifting the hook 53 from the shaft 54 (after releasing the clamping studs 56), the glue box may be moved bodily rearward so as to withdraw the fork members at its forward end from the pins 52. The glue box is freely exposed at the upper rear part of the machine so that it may readily be removed without disturbing other portions of the machine and even while the machine is running, if desired. When the glue box is placed in operative position, the sprocket wheel 45 automatically engages the chain 39, and thus the roll 57 is immediately started into operation as soon as the cam shaft begins to turn.

At the upper forward part of the frame, horizontally fixed and parallel guide rails 59 (Figs. 1 and 3) are arranged, one of these rails being secured to each of the frame members 1 and 2, respectively. These guide rails extend back from the label-applying station almost to the forward edge of the glue box, as shown, for example, in Figs. 2 and 3. These rails define a path for the label-transfer carriage 60 (Figs. 1, 2, 3, 5 and 6) which slides from front to rear along these rails. A pin 60^a (Fig. 3) projects from each side of this carriage 60, and to each pin is pivotally connected the forward end of a link 61 (Fig. 3). The rear end of each link is pivotally secured to the upper part of a long upright rock arm 62 (Figs. 1, 2 and 3). One of these rock arms 62 (Fig. 1) is disposed at each side of the machine, outside of the

frame members 1 and 2, respectively, the lower ends of the rock arms 62 being fixed to a transverse shaft 63 (Fig. 2) which turns in bearings in the frame members 1 and 2. An actuating arm 64 (Figs. 1, 2 and 13) is fixed to the shaft 63 at a point between the right-hand face of the cam disk 16 and the inner face of the frame member 2, and at its upper end carries a stub shaft on which is mounted a cam follower roll 65 (Figs. 11, 13 and 20) which engages the cam groove 18 in the right-hand side of the cam disk 16. This cam is of such contour as to cause the label-transfer carriage to move backwardly and forwardly along the guide rails 59 in the proper sequence relatively to the times of operation of the other parts.

The label-transfer carriage 68 (Figs. 3, 5 and 6) supports the pneumatic pick-up plate or pad 66 which has a substantially flat horizontal under surface. This plate or pad 66 may be of the construction more fully disclosed in my copending application for Letters Patent, Serial No. 166,503, filed June 6, 1950, but is here shown (Fig. 5) as provided with a multitude of vertical suction orifices 67 which communicate with a chamber 68 within the body of the transfer carriage. This chamber 68 communicates, by means of a flexible conduit 70, which is attached to the left-hand actuating arm 62, with an air pump 71 (Figs. 1, 2, 3 and 7) which is mounted at the left-hand side of the machine outside of the frame member 1. As illustrated in Fig. 7, this air pump 71 comprises a cylinder 72 which is open at its bottom and within which slides a trunk piston 73 having a rod 74 which is pivoted at its lower end to a fixed stub shaft 75 (Figs. 1 and 7) projecting outwardly from the frame member 1. The cylinder 72 has a head 76 at its upper end, the head having an upwardly projecting boss 78 whose upper part forms a bearing 78a for the reception of an eccentric pin 79 projecting from the left-hand end (Fig. 4) of cam shaft 12. A transverse air passage 80 in the part 78 extends through a nipple which receives the lower end of the flexible conduit 70. A vertical air passage leads from the space in cylinder 72, above the piston, to the air passage 80. The left-hand end of the passage 80 is normally closed by a valve 81 carried by a lever 82 which is urged toward valve-closing position by a spring 83.

A valve-actuating lever 84 (Fig. 7) is pivoted at 85 upon a fixed stud, the lever 84 resting upon an adjustable eccentric disk 84a which determines the height of the free end of the lever. The free end of the lever is positioned in the orbit of movement of the upper end of the valve lever 82 so that at the proper time, in the cycle of operation, the end of lever 82 is engaged by the lever 84 and is thus swung so as to open the valve.

A fixed vertical bearing 86 (Figs. 1 and 2) is arranged midway between the frame members 1 and 2 with its axis spaced forwardly from the forward edge of the gum box. This bearing 86 provides a vertical guideway for the vertically sliding stem 87 (Figs. 2, 11 and 23) of a picker supporting boss 88 which projects down from the horizontal picker plate 89.

As shown in Fig. 23, the boss 88 is hollow, and internally screw-threaded and is integral with the picker 89. A clamping nut 88a, turning freely on the upper end of the stem 87, has threaded engagement with the part 88 and is provided with a head 88b by means of which it may be turned. The stem 87 has spaced, peripheral grooves which receive snap rings 88c and 88d. When the nut 75

88a engages the ring 88d, rotation of the nut will draw the picker boss 88 down into firm contact with the upper end of the stem 87. By turning the nut 88a in the other direction, the picker boss 88 may be freed from the stem. The ring 88d limits downward movement of the nut on the stem. By this means it is readily possible to exchange picker plates for others of different sizes or shapes.

The upper end of the stem 87 has a radial slot 88e (Fig. 23) which receives a pin 88f projecting down from the picker plate, thus preventing relative rotation of the picker and stem. The picker plate has a smoothly finished, horizontal upper surface designed to receive a coating of glue. Preferably, the rear edge of the picker plate is beveled, as shown at B.

At its lower end the stem 87 is pivotally connected (Figs. 2 and 11) to the upper end of a link 92 whose lower end is pivoted to the forward end of a curved picker lever 93, having a hub 93a (Figs. 4 and 11) which turns on the shaft 23. The lever 93 has a downwardly extending arm carrying a cam follower roll 95 which bears against the peripheral cam surface 20 of the cam disk. A spring 96 (Fig. 11) tends to swing the arm 93 in a clockwise direction and thus to move the picker upwardly toward the magazine M which is arranged directly above the picker and in which labels L are held in the usual manner by the fingers 97.

The magazine may be of conventional type with provision for adjusting the fingers 97 to accommodate labels of different sizes, the magazine being supported for vertical adjustment by a sleeve S (Fig. 2) which is adjustable vertically along a rod projecting upwardly from the right-hand frame member.

The forward end of the arm 93 (that is to say, the left-hand end as viewed in Fig. 11) is provided with a notch 98 (Fig. 22) designed to cooperate with stop mechanism whereby the picking operation may be stopped temporarily, if desired, although the machine may continue to operate. Such a mode of action may be desirable when starting the machine up in order to insure a proper coating of adhesive on the picker before the latter is allowed to approach the magazine.

This stop mechanism (Figs. 19 to 22) comprises parts which are supported by a rearwardly projecting shelf 99 (Fig. 20) which forms an integral part of a front plate 100 (Fig. 1) which is bolted to the plate members 1 and 2. This shelf has spaced bearings for a shaft 101 (Fig. 20) to which is fixed one end of a lever 102 (Fig. 21) provided at one end with a horizontal portion 102a (below the shelf 99), having a socket 103 in its outer face and an aperture below the socket. The socket 103 receives a ball 104 at the right-hand end of a rod 105 arranged to slide and rock in an opening 106 in a downwardly directed flange 107 forming part of the shelf 99. A compression spring 108, embracing the rod 105, bears against a collar 109 on the rod 105 and urges the rod toward the right, as viewed in Fig. 21. A latch arm 108a has a hub 110 which is loosely hung on the shaft 101, the hub 110 having diametrically arranged radial shoulders 110a (Fig. 27) which are engaged, respectively, by the ends of the parallel arms 111 of a fork 111a (Fig. 28) having a stem 112 which slides in the aforesaid aperture in the part 102a. A coiled compression spring 113 embraces the stem 112, one end of the spring abutting the part 102a and its other end engaging the head of the fork 111a. The parts 102 and 105 thus function

as toggle links. The spring 113 urges the fork toward the right, as viewed in Fig. 21, and thus tends to hold the latch arm 108^a in the position, relative to the lever 102, shown in Fig. 21. A hand lever D is fixed to the shaft 101. By moving this hand lever, the arm 102 may be swung downwardly until the socket 103 in the part 102^a is below the center line through the axes of the shaft 101 and the aperture 106 in the part 107, whereupon the spring 108 becomes effective to snap the parts down to the position shown in Fig. 19. A stop 115, forming part of the lever 102, contacts the underside of shelf 99 when the parts are in the position shown in Fig. 19, thus preventing over-throw of the hand lever.

A latch dog 116 (Fig. 21) is mounted to slide between the front face of the latch arm 108^a and a retaining plate 117 which is secured in spaced relation to the arm 108^a by bolts 118. This dog 116 has an acute lower edge 119 which, at times, may engage the notch 98 (Fig. 22) at the left-hand end of the lever 93. The dog 116 is connected by parallel links 120 (Fig. 19) to a lever arm 121 having a cam roll 121^x (Fig. 2) arranged to engage cam path 17 in cam disk 16.

During the normal operation of the machine, the hand lever D is in the rearward position shown in Fig. 20, and the lower edge of the locking dog 116 is out of the path of the notched forward end of the lever 93 as the latter moves up and down to actuate picker. During this normal operation, the dog 116 is moved idly up and down along the arm 108^a by the lever 121. If at this time the handle D be moved forwardly, the lower edge 119 of the dog 116 may contact the vertical face 98^a (Fig. 22) just below the notch 98 in lever 93, but it can not enter the notch until member 116 has been moved to engaging position by lever 121. This occurs at about 75° (see Fig. 30). The cam 20, which operates the picker, is provided at one point in its periphery with a hump H (Figs. 12 and 20) of an arcuate extent of, for example, 30°, whose effect is to move the picker lever 93 down to a point lower than that necessary for the performance of the picking cycle. The picker and presser operating cams are so timed that when the hump H of the picker cam has moved the notch 98 down to its lowest possible point, the lever 121 will have moved the dog 116 to its highest position, thus permitting the point 119 to enter or leave the notch.

The picker arm 93 is elevated by the spring 96 (Fig. 20) which is attached to an arm 93^x integral with the picker arm 93, and is moved downwardly by the cam 20. When the latch dog 116 is disengaged from the notch 98, under normal operating conditions, the picker lever 93 is free to move through its normal cycle. During its up-stroke, it pauses to transfer the label and receive glue from the roller 129, mounted on the carriage 60, and then drops slightly due to the hump H on the cam; then moves on up to the picking position to take a label from the magazine. It then moves down, bringing a label with it, to a point below glue-receiving and transfer position until carriage 60 has reached the rear end of its travel; the picker then rises with the label to transfer level, which is so close to the plane of the lower face of the transfer carriage that the label may be transferred pneumatically from the picker to the carriage.

However, if it be desired, for example, in starting the machine, to insure a good coating of glue on the picker before the latter is elevated to the picking position, the operator urges the

handle D forwardly, and when the hump H of cam 20 positions the lever 93 at its lowest point, the dog 116 may enter into the notch 98, and the toggle linkage, comprising the parts 102 and 105, becomes effective to retain the handle D in the forward position until it is manually pushed back. As the cam 20 continues to turn, the spring 96 is unable to elevate the picker arm 93, the latter being held down by the dog 116 so that it can not rise higher than the glue-receiving level. So long as the handle D remains in this forward position and the machine continues to operate, the picker will rise to the level shown in Fig. 19 and receive glue at each cycle of operation, the gum-applying roll being able to contact the picker either at the transfer level (Fig. 14) or at the lower level shown in Fig. 19, but the picker will not be able to rise to take a label from the mechanism or to apply glue to the lower surface of the carriage. When the operator is sure that the picker has been provided with a good coat of glue, the operator will urge the handle D rearwardly, and when the picker lever 93 is at its lowest possible position, the dog 116 will be withdrawn from the notch 98 by action of spring 113, thus permitting resumption of normal operation. By the arrangement above described, it is impossible to place the parts in position for resumption of picking except when the several parts are at the proper relative position in the cycle of movement. Otherwise it might be possible to get the parts out of time so that the glue covered picker would rise and coat the underside of the transfer carriage with glue.

A bell-crank lever (Fig. 13) having a forwardly extending arm 109^x, is mounted to turn on the transverse shaft 54 which supports the rear part of the gum box. A bracket 110^x is fixed to the forward end of the arm 109^x, and to this bracket is secured a cradle 111^x which is designed to hold the article which is to be labeled. The cradle 111^x is removably secured to the carrier 104^x so that cradles of different types may be applied in accordance with the particular article to be labeled.

The bell-crank lever also comprises the downwardly extending arm 112^x (Figs. 2 and 13) having a cam follower roll 113^x at its lower end which engages the peripheral cam surface 19 of the cam disk 16. A spring 109^a (Fig. 13) tends to raise the arm 109^x, the downward movement of the arm 109^x being a positive movement by the action of the cam. Downward movement of the arm 109^x is limited by contact of a part 114 of the bracket 110^x with the shelf 99.

A lever 116^x (Figs. 2 and 12) is fulcrumed at its rear end on the left-hand end of rod 54 and at its forward end has a transversely extending part 117^x to which is removably secured a presser or wiper device 118^x. This presser device 118^x may be of any desired type proper to wipe and/or press the label into adhesive contact with the article supported at the labeling station. For example, it may be of the kind illustrated in the patent to Sjoberg, No. 2,292,093, August 4, 1942, or it may be designed specifically to apply both wiping and direct pressing action to the label. The particular form of presser is immaterial to the present invention.

A lever 120^x (Figs. 2, 12 and 20) has a hub 122 (Figs. 1 and 4) which turns on the shaft 23. At its forward end the lever has a transversely extending portion 121^a (Fig. 26) provided with a horizontal, axial bore which receives a

shaft 123. This shaft has a peripheral groove which receives a set screw 123^x (Fig. 26) which holds the shaft 123 in place in the part 121^a. At its left-hand end (Fig. 26) the shaft 123 has a head 124 provided with a transverse bore through which passes the lower portion of a rod 119^x. Stop nuts 124^x on the rod 123^x limit the downward movement of the latter through the part 124. A coiled compression spring 125 embraces the rod 119^x below the head 124, the lower end of the spring resting upon a nut 124^m on the end of the rod 119^x.

The label-transfer carriage 60 is provided at each side (Figs. 3, 5, 6 and 12) with a rearwardly extending rigid arm 126, each arm being provided at its rear end with a vertical slot 127 (Fig. 12) open at its upper end and which is designed to receive a trunnion 128 projecting from one end, respectively, of the glue-applying roll 129 above referred to. With this arrangement the roll 129 is free to rise and fall relatively to the transfer carriage.

An alternative arrangement for removably mounting the shaft of the gum-transfer roll in the transfer carriage is illustrated in Fig. 25. In this view, one of the rearwardly extending arms 126^m of the transfer carriage is shown as provided at its rear end with a downwardly and rearwardly directed finger 200 having a substantially horizontal upper surface forming the floor of a horizontal recess 201 of a vertical depth sufficient to receive the shaft 128 (Fig. 24) on which turns the hollow core or sleeve 129^m of the gum transfer roll 129^a. The end portion of the arm 126^m is provided with a vertical screw-threaded bore for the reception of a manually adjustable screw 201^a having a conical tip 202 which may be forced into contact with the shaft 128 so as to prevent the shaft from rotating. By retraction of the screw 201^a, the roll may readily be removed from the carriage.

The gum-applying roll 129^a should be resiliently yieldable to a high degree, and for this reason it is preferably of the construction shown in detail in Fig. 24. The roll, as thus shown, comprises a tubular metallic core 129^m which is mounted to turn on the shaft 128, and a cylindrical body portion 129^a of rubber molded about the core. In order to obtain the desired degree of resilient yieldability, the body of rubber is so molded as to have one or more annular series of longitudinally extending holes 129^x. As here shown, two concentric series of holes are provided, the holes of the inner series being of smaller diameter than those of the other series. With this arrangement a very soft and yielding roll is provided which is highly effective in spreading a uniform coating of adhesive over the picker plate.

The gum-transfer roll is designed to apply gum to the picker when the latter is at the normal transfer level and also when the picker is at the preliminary gumming level at which it is positioned during the starting of the machine. Thus, the roll must be capable of rising and falling as illustrated in Fig. 12, or of a very substantial degree of radical compression, as shown in Fig. 24, to enable it to contact the picker in both of these positions.

Operation

The operation of the machine may be best understood by reference to certain of the steps taken in sequence. Assume that the machine is in operation, that the magazine has been sup-

plied with labels, that a bottle A has been placed in the article-receiving cradle, that the gum box has been supplied with gum, and that the upper surface of the picker plate 89 has also received a coating of gum (the handle D being in the forward position). The cycle of operations may be considered as starting with the parts as shown in the position of Fig. 11. In this position, the label transfer carriage 60 is at the labeling station, disposed directly above the article A resting on the cradle 111^x. At this time the cradle 111^x is in its lowest position with the part 114 contacting shelf 99. At the same time, the picker has been raised to the maximum elevation, and the gum-coated picker plate 89 is contacting the lowermost of the labels L in the magazine M. It will also be noted that a label L' is adhering to the underside of the suction plate 66 of the pneumatic transfer carriage. The next step is illustrated in Fig. 16. The cradle 111^x has been raised by the action of the cam 19 so as to bring the surface of the article A into contact with the adhesively coated label L'. The picker is still in the picking position. The result of the next step is shown in Fig. 12. The label L' now rests upon the article A, while the cradle 111^x has resumed its normal low position; the picker 89 has moved downwardly to its lowest normal position where it is too low to be contacted by the gum-transfer roll 129 and the transfer carriage 60 is on its way back toward the gum box. It may be noted that at this particular point the presser 118^x is on its way down and is just clear of the forward portion of the transfer carriage, the timing of the parts being such as to allow a minimum clearance, thus saving time in operation.

As shown in Fig. 17, the picker is still in its lowermost normal position, the transfer carriage has moved a little further to the rear, and the presser 118 has moved down into contact with the label L' and is pressing the latter firmly against the bottle A. At this time the cradle is rigidly supported (as shown in Fig. 13) by contact of the part 114 with the shelf 99.

Referring now to Figs. 13 and 18, the labeled bottle has been removed from the cradle 111^x and the latter is ready to receive another bottle. The presser 118 has moved up to its idle position; the picker is still too low to contact the transfer carriage, and the latter has moved rearwardly to the end of its rearward stroke, bringing the applying roll 192 into contact with the glue-elevating roll 57. The latter roll is rotating and thus causes the roll 129 to turn while applying a coating of glue to its peripheral surface.

The picker now rises, (carrying with it that label L² which it has last removed from the magazine), to the transfer and gum-receiving level, the label being now disposed directly below the plane of the lower surface of the suction plate 66 of the transfer carriage. As the carriage starts forwardly, suction is created by pump 71 at the suction orifices 67 (Fig. 5) so that the label preferentially adheres to the transfer carriage. The latter drags the label with it, sliding the label off of the gummed upper surface of the picker, and in doing so insures a uniform distribution of the glue coating over the label. Before the label has been completely removed from the upper surface of the picker plate, the roll 129 (Fig. 14) has come in contact with the rear margin of the plate 89 (riding up over the beveled rear margin B of the plate) and, as the carriage

proceeds, the roll 129 applies a new coating of glue to the upper surface of the picker.

The carriage continues its forward movement until it arrives at the position shown in Fig. 11. During the completion of the forward motion of the carriage, the picker 89 moves upwardly from the transfer level toward the magazine, reaching the latter and applying its glue-coated surface to the lowermost label in the magazine at about the time the carriage reaches the labeling station, as shown in Fig. 11, thus completing the cycle.

In terms of a complete revolution of the cam shaft (Fig. 30) and assuming a zero degree starting point, with the transfer carriage and picker at the transfer station, during the first 60° of rotation of the cam shaft, the picker remains at the transfer level and the piston 73 is moving and starting to create a vacuum in the cylinder 72. At this time the presser is dwelling at its uppermost position. Between 60 and 75° the picker moves down slightly, but between 75° and 130° it moves to the picking level; meantime the carriage continues forwardly to the 90° position (which is the labeling position), and between 75° and 120° the cradle rises to bring the article A into contact with the label which is adherent to the underside of the transfer carriage. The cradle dwells between 120° and 125°; maximum vacuum is obtained at about 80°, and at that point the valve-actuating lever 82 (Fig. 7) contacts the lever 84, thus opening the valve 81 and breaking the vacuum at the pad 66, thus freeing the label which now rests on the upper surface of the article A. The transfer carriage dwells between 90° and 155°; the cradle starts down at approximately 125° and reaches its normal low level at 172° where it dwells during the remainder of the cycle.

At about 130° the picker begins to descend and reaches its lowest normal level at about 185°. The carriage starts back toward the transfer point at about 155°, just escaping the downwardly moving presser 118. The latter descends and contacts the label on the article between 235° and 265° and then returns to its uppermost position where it dwells during the remainder of the cycle. The picker begins to rise at about 185° and continues to rise up to 230° where it is at the transfer and gum-receiving level, where it dwells throughout the remainder of the cycle. Relative motion of the piston and cylinder starts to build up vacuum at about 260°, sucking in air through the ports 67 until the ports are covered by the label as the picker arrives at the transfer level at 230°.

The cycle of operations is very simple, and there is almost no loss of time in waiting for any one operation to be completed before some other step in the operation begins. Thus, as noted, the label is not fully stripped from the picker before a new coating of glue begins to be applied to the picker. In the same way the empty transfer carriage, in starting rearwardly, barely escapes the downwardly moving presser device, and, in making its up and down stroke, the picker passes through the transfer station but without interference with the carriage while the latter is completing its forward movement, and descends to a level to avoid contact with the carriage as the latter returns to the transfer station. The machine is thus capable of operating at very high speed, but, as the paths of movement are short, there is little tendency to set up heavy vibrations and the machine operates

quietly. The machine comprises relatively few parts, as compared with most machines of this general type, and may be built at reasonable cost. The gum box with its appurtenances is readily removable for cleaning and easy of replacement without dismantling the machine or even requiring the removal of any attaching or connecting elements. The magazine is easily accessible and the speed of the machine is readily changed without recourse to complicated speed reduction gear trains or similar devices. Moreover, the temporary cessation of picking, to insure a proper coating of the picker in starting up, can not possibly result in getting the parts out of proper time.

While one desirable embodiment of the invention has been illustrated by way of example, it is to be understood that the invention is broadly inclusive of any and all modifications falling within the scope of the appended claims.

I claim:

1. In combination in a labeling machine having a magazine and a picker, means guiding the picker to move in a rectilinear path, means for holding the picker stationary while gum is being applied to it, means for moving the picker toward the magazine to bring its gum-coated surface into contact with the endmost label in the magazine, means operative to move the picker with its adhering label back to the gum-receiving position, and means operative to remove the label from the picker while the latter dwells at the gum-receiving position.

2. In combination in a labeling machine of the kind having a magazine, a picker movable toward and from the magazine, a transfer carrier movable in a substantially horizontal path intersecting that of the picker, means for causing the picker to dwell in a position immediately below the path of the carrier, means to move the carrier along its path toward a label-applying station and to cause it to dwell directly above the picker while a label on the picker is being gripped by the carrier, the carrier then moving toward the applying station, and means operative to apply gum to the picker while it continues to dwell in the transfer position, after the label has been transferred to the carrier.

3. In combination in a labeling machine of the kind having a magazine, a picker movable along a substantially vertical path toward and from the magazine, means for applying adhesive to the picker, a transfer carrier movable in a path intersecting that of the picker, means for causing the picker to dwell in a position immediately below the path of the carrier, means operative so to move the carrier back and forth along its path that it dwells in registry with the picker while a label on the picker is gripped by the carrier, then moves along its path to a label-affixing station and then reverses its direction and returns to the transfer point, and means operative to depress the picker during the return travel of the carrier thereby to prevent contact of the carrier and the adhesively coated picker.

4. In combination in a labeling machine of the kind having a magazine, a picker movable toward and from the magazine, a transfer carrier movable in a path intersecting that of the picker, means for causing the picker to dwell in a position immediately below the path of the carrier, means operative so to move the carrier back and forth along its path so that it dwells in registry with the picker while the picker rises to permit a label carried by the picker to be

gripped by the carrier, then moves to a label-affixing station and then reverses its direction of movement and returns to the transfer station, a picker-gumming roll mounted on the carrier and which applies gum to the picker as the carrier leaves the transfer point in moving toward the label-affixing station, and means operative to move the picker to a position such as to prevent contact of the gumming roll and the picker as the carrier moves in the reverse direction.

5. In a labeling machine, a transfer carrier which moves back and forth in a rectilinear path between a gum supply and a labeling station, a picker which moves in a rectilinear path intersecting that of the carrier, a magazine arranged to deliver a label to the picker at one end of the path of movement of the latter, means for moving the carrier and picker along their respective paths and to cause them to dwell at a transfer station at the intersection of the picker and carrier paths where the carrier receives a label from the picker, and means operative to apply adhesive to the picker while it dwells at said station.

6. In combination in a labeling machine, a picker, means for sliding a label from off the picker, and means for applying a coating of adhesive to the picker concomitantly with the removal of the label from the latter.

7. In a labeling machine, in combination, a picker, means operative to pull a label from off the picker in such a way as progressively to expose an increasing area of the picker, and means operative to apply adhesive to the picker as the surface of the latter is exposed by the withdrawal of the label.

8. In combination in a labeling machine, a picker having a substantially flat surface for the reception of adhesive, a carrier operative to grip a label resting on the adhesively coated surface of the picker and to remove the label from the picker by sliding the label parallel to the surface of the picker, and adhesive spreading means operative progressively to apply adhesive to the surface of the picker as said surface is progressively exposed by removal of the label.

9. In a labeling machine, in combination, a picker having a label-supporting surface, a carrier operative to grip a label resting on the supporting surface of the picker, means for moving the carrier, while it grips the label, so as to slide the label over the picker surface and across one edge of the latter until the label is completely removed from the picker, and a gum-applying device which follows the carrier and which starts to apply adhesive to the picker surface, beginning at the opposite edge of the latter, before the label has been completely removed from the picker.

10. In combination in a labeling machine, a magazine for labels so arranged that the lowermost label is substantially horizontal, a movable picker and means for guiding it in a vertical path toward and from the magazine, a movable transfer carrier and means for moving it in a horizontal path intersecting the path of the picker, means for moving the picker to and from the magazine and for causing it to dwell at a transfer level, a gum supply, a gum-applying device mounted on the carrier, means, including a cam, operative to move the carrier to a position where the gum-applying device receives gum from the supply, and then to move the carrier relatively to the picker to strip the label from

the picker while the gum-applying device is concomitantly applying gum to the picker.

11. In combination in a labeling machine, a transfer carrier operative to grip and to remove a gummed label from a picker, and means connected to the transfer carrier for applying gum to the picker as the label is removed from the latter.

12. In combination in a labeling machine having a magazine, a picker and a transfer carrier for moving a label from the picker to a labeling station, means mounted on the transfer carrier for applying gum to the picker.

13. In combination in a labeling machine having a magazine, a picker and a transfer carrier, a gum-transfer roll supported by the carrier.

14. In combination in a labeling machine of the kind wherein a label carrier moves back and forth along a predetermined substantially horizontal path, a picker to which adhesive is applied, a gum-supplying reservoir, and a gum-applying roll mounted on the carrier and which is operative, as the carrier moves along its path, to transfer gum from the supply to the picker.

15. In a labeling machine, in combination, a magazine for labels, a picker, a transfer carrier, means for moving the transfer carrier back and forth along a predetermined path, means, including a cam, for moving the picker in a path which intersects the path of the carrier at substantially right angles, the means for moving the picker being so constructed and arranged as to cause the picker to dwell at a transfer station at which the label carried by the picker is gripped by the carrier, a gum supply, and means mounted on the transfer carrier which first removes gum from the supply, and which thereafter deposits the gum upon the picker while the latter dwells at the transfer station.

16. In combination in a labeling machine, a magazine for labels, a picker which moves in a path substantially perpendicular to the surface of the endmost label in the magazine, a transfer carrier which moves in a path which intersects the path of the picker, means for moving the picker and for causing it to dwell at a transfer station at which the carrier grips a label mounted on the picker, means for moving the carrier along its path away from the transfer station carrying the label with it, and a gum-applying device mounted on the carrier and which is operative to apply a coat of gum to the picker while the latter dwells at the transfer station.

17. In a labeling machine, in combination, a picker having a label-supporting surface, a carrier operative to grip a label resting on the supporting surface of the picker, means for moving the carrier while it grips the label, so as to slide the label over the picker surface across one edge of the latter until the label is completely removed from the picker, and a gum-applying device connected to the carrier and which applies gum to the picker surface as the latter is being exposed by removal of the label, the application of gum beginning at the opposite edge of the picker.

18. In a labeling machine, in combination, a carrier guided to move in a predetermined path between a label-applying station and a gum supply, a magazine for labels, a picker guided to move toward and from the magazine in a path which intersects that of the carrier, picker-actuating means, including a cam, for advancing the picker toward the magazine to receive a label from the latter, said picker-actuating means be-

ing so constructed and arranged as to move the picker away from the magazine and cause it to dwell at a point such that the carrier may intersect the path of the picker, without contact with the picker, on its way toward the gum supply, the picker-actuating means being operative to move the picker to a transfer station and to cause it to dwell there while the carrier grips the label carried by the picker, and a roll, supported by the carrier operative first to take gum from the supply and then, while the picker dwells at the transfer station, to apply gum to the picker.

19. In combination in a labeling machine of the kind wherein a label carrier moves back and forth along a predetermined path, a picker to which adhesive is applied, a gum-supplying reservoir, the carrier having open-ended slots for the reception of a roll-supporting shaft, a shaft mounted in said slots and removable at will therefrom, and a gum-applying roll mounted on the shaft and which is operative to take gum from the supply and, as the carrier moves along its path, to apply the gum to the picker.

20. In combination in a labeling machine of the kind wherein a label carrier moves back and forth along a predetermined path, a picker to which adhesive is applied, a gum-supplying reservoir, the carrier having substantially horizontal open-ended slots for the reception of the opposite ends, respectively, of a roll-supporting shaft, means for releasably securing a roll-supporting shaft within said slots, and a gum-applying roll mounted to turn freely on said shaft and operative to take gum from the supply, and as the carrier moves along its path, to apply the gum to the picker.

21. In a labeling machine, in combination, a transfer carrier guided to move back and forth in a predetermined path between a gum supply and a labeling station, the gum supply comprising a receptacle for fluid adhesive and a driven roll which dips in the adhesive, and a gum-applying device mounted on the carrier and which contacts said driven roll when the carrier is at one end of its path of movement, the carrier being constructed and arranged to remove a label from the picker and to carry it to the labeling station.

22. In combination in a labeling machine comprising means operative to move a transfer carrier back and forth along a rectilinear path from a gum-receiving and transfer station to a label-affixing station and then back to the gum-receiving and transfer station, and wherein a picker moves transversely across the plane of movement of the carrier and after receiving a label from a magazine crosses the plane of movement of the carrier and dwells at the transfer station while its label is taken by the carrier, a gum-applying roll mounted on the carrier and which is operative to apply gum to the picker as the carrier moves along its path toward the label-affixing station, said gum-applying roll comprising a cylindrical body of rubber provided with a series of passages extending through it from end to end and which are radially spaced from the axis of the roll.

23. In combination in a labeling machine comprising means, including a cam, operative to move a transfer carrier back and forth along a rectilinear path from a gum-receiving and transfer station to a label-affixing station and then back to the gum-receiving and transfer station, and wherein a picker receives a label from a magazine and dwells at the transfer station while its label

is taken by the carrier, a gum-applying roll mounted on the carrier and which is operative to apply gum to the picker as the carrier moves along its path, said gum-applying roll comprising a cylindrical body of rubber provided with a plurality of concentric series of passages extending through it from end to end, the passages of one series being of greater diameter than those of the other, the roll being highly resilient and readily yieldable in response to pressure.

24. In combination in a labeling machine wherein means, including a power-driven rotary cam, moves a transfer carrier back and forth along a rectilinear path from a gum-receiving and transfer station to a label-affixing station and then back to the gum-receiving and transfer station, and wherein a picker receives a label from a magazine and dwells at the transfer station while its label is taken by the carrier, a gum-applying roll mounted on the carrier and which is operative to apply gum to the picker as the carrier moves along its path, said gum-applying roll comprising a hollow, rigid shaft and a cylindrical body of rubber molded about said shaft, said body of rubber having internal chambers whereby the roll is resiliently yieldable to a high degree.

25. In combination in a labeling machine wherein a rotary cam moves a transfer carrier back and forth along a rectilinear path from a gum-receiving and transfer station to a label-affixing station and then back to the gum-receiving and transfer station, and wherein a picker receives a label from a magazine and dwells at the transfer station while its label is taken by the carrier, a gum-applying roll mounted on the carrier and which is operative to apply gum to the picker as the carrier moves along its path, said gum-applying roll comprising a hollow, rigid shaft and a cylindrical body of rubber molded about said shaft, said body of rubber having internal chambers whereby the roll is resiliently yieldable to a high degree.

26. In a machine of the class described having in combination an adhesive-type picker, means for moving the picker in a predetermined path toward and from a magazine and which normally causes the picker to dwell at an adhesive-receiving level as it moves along said path, a roll for applying adhesive to the picker while the latter dwells at said receiving level, means operative to move the applying roll bodily in a path which intersects that of the picker, thereby to spread adhesive over the picker while the latter is stationary at said receiving level, said roll being actuated uninterruptedly cycle after cycle during the normal machine operation, and manually controlled means for holding the picker at another gum-receiving level during a plurality of successive cycles and while the roll passes across it one or more times.

27. In combination in a labeling machine comprising means operative to move a transfer carrier back and forth along a path from a gum-receiving and transfer station to a label-affixing station and then back to the gum-receiving and transfer station, and wherein a picker receives a label from a magazine and dwells at the transfer station while its label is taken by the carrier, a gum-applying roll mounted on the carrier and which applies gum to the picker, picker-actuating means normally operative to move the picker toward and from the magazine, and means operative, at times, to prevent the picker from approaching the magazine but to permit it to reach a gum-receiving position while the carrier continues to move back and forth.

28. In combination in a labeling machine comprising means, including a cam, operative to move a transfer carrier back and forth along a substantially rectilinear path from a gum-receiving and transfer station to a label-affixing station and then back to the gum-receiving and transfer station, and wherein a picker receives a label from a magazine and dwells at a transfer level while its label is taken by the carrier, a gum-applying roll mounted on the carrier, said roll being constructed and arranged to apply gum to the picker, during the motion of the carrier in one direction, while the picker is at the transfer level, or alternatively when it is at another level, picker-actuating means normally operative to move the picker from the magazine to the transfer level, and means operative, at times, to move the picker to said other level while the carrier continues to make gum-applying strokes.

29. In combination in a labeling machine, a magazine, a picker movable toward and from the magazine, a spring tending to move the picker toward the magazine, a cam operative to move the picker away from the magazine, and manually controlled means to prevent approach of the picker to the magazine.

30. In combination in a labeling machine, a magazine, a picker movable toward and from the magazine, a spring tending to move the picker toward the magazine, a cam-actuated part operative to move the picker away from the magazine, a stop engagable with said part to limit movement of the picker toward the magazine, and manually controlled means for moving said stop into and out of operative position.

31. In combination in a labeling machine of the kind wherein a rotating shaft, through the intermediary of appropriate mechanism, causes a gum-coated picker to take a label from a magazine and carry it to a transfer position where it is taken by a carrier, and a gum applying device operative to coat the picker with gum preparatory to the picking operation, manually controlled interrupter means operative to prevent the picker from reaching the transfer position although the shaft continues to rotate, and control means operative to prevent such action of the interrupter means except when the picker and carrier mechanisms occupy a predetermined relative relation.

32. In a machine of the class described having in combination an adhesive type picker, means for moving the picker in a predetermined path toward and from a magazine and which normally momentarily stops the picker at an adhesive-receiving level as it moves along said path, a device for applying adhesive to the picker while it dwells at said receiving level, means for actuating the applying device uninterruptedly cycle after cycle during the normal operation of the machine, and manually actuatable means operative to detain the picker at another level at which it likewise receives adhesive from the applying device during a plurality of cycles of operation of the machine.

33. In combination in a labeling machine, a magazine, a picker adapted to carry a label from the magazine to a transfer point, a spring tending to move the picker toward the magazine, a cam-actuated lever operative to move the picker away from the magazine, a rock-arm supporting a slidable detent which is engageable, at times, with a notch in said cam-actuated lever thereby to limit movement of the picker toward the transfer point, a rotary shaft having mounted

thereon a cam for actuating the picker-operating lever, said cam having an active portion operative, during a predetermined limited arc of rotation of the shaft, to locate the picker-actuating lever in a position in which the detent may enter or leave the notch, and another cam-actuated part for reciprocating the slidable detent along its supporting rock-arm thereby, when the detent is engaged with said notch, to prevent the picker from reaching the transfer point although the cam shaft continues to rotate, and manually actuatable means for swinging the rock-arm to move the detent toward or from notch-engaging position.

34. In combination in a labeling machine of the kind wherein a rotating shaft through the intermediary of appropriate mechanism, causes a gum-coated picker to take a label from a magazine and move it to a transfer station where it is gripped by a movable carrier, and an applying device operative to coat the picker with gum preparatory to the picking operation, manually controlled interrupter means operative to prevent the picker from arriving at the transfer station while permitting it to take a gum-receiving position while the shaft continues to rotate, said interrupter means comprising a stop element movable into the path of a part of the picker-actuating mechanism, and means operative to prevent engagement or disengagement of said stop element and part except within a predetermined limited arc of the shaft's rotation.

35. In combination in a labeling machine, a magazine, a picker movable toward and from the magazine, a spring tending to move the picker toward the magazine, a cam-actuated lever operative to move the picker away from the magazine, a stop member engageable with said lever to limit movement of the picker toward the magazine, a manually actuatable handle for moving the stop toward and from operative position, and automatic means for holding the stop in the position in which it is placed by actuation of the handle.

36. In combination in a labeling machine, a magazine, a picker movable toward and from the magazine, a spring tending to move the picker toward the magazine, a cam-actuated lever operative to move the picker away from the magazine, a stop member engageable with said lever to limit movement of the picker toward the magazine, a manually actuatable handle for moving the stop member toward and from operative position, and snap-action means operative to retain the stop member temporarily in the position to which it is moved by the handle.

37. In combination in a labeling machine, a magazine, a picker adapted to carry a label from the magazine to a transfer point, means for moving the picker toward the magazine, a cam-actuated part operative to move the picker away from the magazine, a lever arm carrying a detent which is engageable, at times, with said cam-actuated part thereby to limit movement of the picker toward the transfer point, a handle for rocking said lever to move the detent toward operative position, and a spring-loaded toggle linkage operative to hold the handle temporarily in the position to which it is moved.

38. In combination in a labeling machine, a magazine, a picker adapted to carry a label from the magazine to a transfer point, means for moving the picker toward the magazine, a cam and a lever actuated thereby operative to move the picker away from the magazine, a rock-arm carrying a detent which is engageable, at times,

with said cam-actuated lever thereby to limit movement of the picker toward the transfer point, a handle for swinging said rock-arm so as to move the detent toward the operative position, snap-action means operative to retain the handle temporarily in the position to which it is moved, said cam being so shaped as to prevent engagement of the detent with the lever except within a predetermined arc of the cam's rotation.

39. In a labeling machine, in combination, a label transfer carrier which moves from a labeling station at the front of the machine to a gum supply at the rear of the machine, the gum supply comprising a gum reservoir having a fork at its forward end, a fixed, transversely extending pin which is received between the tines of the fork to support the forward edge of the reservoir, the reservoir having a downwardly open hook at its rear end, and a transverse shaft on which said hook normally rests, the reservoir being free to be lifted from its supports.

40. In combination, in a labeling machine having a pair of side frame members and means rigidly connecting them in spaced relation, in combination, guide means carried by the frame members defining a path for a transfer carrier movable from a labeling station at the front of the machine to a gum supply at the rear of the machine, a cam shaft, and a carrier-actuating cam thereon interposed between said frame members and below said path, a gum box interposed between said frame members at the rear terminus of said path, said gum box being freely exposed for removal in an upward direction, and parts carried by the frame members for removably supporting the gum box.

41. In combination, in a labeling machine having a pair of side frame members and means rigidly connecting them in spaced relation, in combination, guide means carried by the frame members defining a path for a transfer carrier movable from a labeling station at the front of the machine to a gum supply at the rear of the machine, a cam shaft, and a carrier-actuating cam thereon interposed between said frame members and below said path, a gum box interposed between said frame members at the rear terminus of said path, said gum box being freely exposed for removal in an upward direction, fixed, aligned horizontal pins projecting inwardly from the opposite frame members respectively, the gum box having supporting elements at its forward part designed to rest upon said pins, a shaft extending transversely across from one frame member to the other at the rear of the gum box, and a part rigidly connected to the gum box and which normally rests upon said shaft thereby to support the gum box in operative position.

42. In combination in a labeling machine of the kind which includes a suction type transfer carrier having an interior chamber and suction orifices communicating therewith, means guiding the carrier to move back and forth along a predetermined path from a labeling station to a transfer station, and carrier-actuating means operative to cause the carrier to dwell at the transfer station and again at the labeling station, a suction device operative to establish sub-atmospheric pressure in the interior chamber of the carrier, a normally closed valve closing a passage leading to said chamber, and means operative, while the carrier dwells at the labeling station, to open said valve.

43. In combination in a labeling machine of the kind which includes a suction type transfer

carrier, means for moving it in a predetermined path, said carrier having an interior chamber and suction orifices communicating therewith, a suction device comprising a cylinder and a piston therein, the piston having a rod whose free end is pivotally attached to a fixed support, a rotatable shaft, means carried by the shaft for moving the cylinder relatively to the piston, and a flexible conduit which always provides free communication between the interior of the cylinder and the chamber of the carrier.

44. In combination in a labeling machine of the kind which includes a suction type transfer carrier having an interior chamber and suction orifices communicating therewith, a cam shaft having a cam thereon for actuating the carrier, a suction device comprising a cylinder open at one end and a piston slidable in the cylinder, the piston having a rod which extends out through the open end of the cylinder, means pivotally connecting the free end of the piston rod to a fixed part, an unobstructed conduit which always connects the interior of the cylinder with the chamber of the carrier, an eccentric on the cam shaft, and means for transmitting motion from the eccentric to the cylinder thereby to move the latter relative to the piston.

45. In combination in a labeling machine of the kind which includes a suction type transfer carrier having an interior chamber and suction orifices communicating therewith, means guiding the carrier to move back and forth along a predetermined path from a labeling station to a transfer station, carrier-moving means operative to cause the carrier to dwell at the transfer station and again at the labeling station, a suction device comprising a cylinder and a piston, the latter having a rod, means for pivotally connecting the free end of the piston rod to a fixed part, the cylinder having a head at one end within which is a passage opening at one end to the atmosphere, a flexible unobstructed conduit leading from the other end of said passage to the chamber in the carrier, a rotary shaft, an eccentric on the shaft, the cylinder head having a part which constitutes an eccentric strap embracing the eccentric, a valve normally closing that end to said passage which communicates with the atmosphere, and a part operative, as the cylinder is moved by the eccentric, to open said valve while the carrier dwells at the labeling station.

46. In combination in a labeling machine of the kind wherein a suction device moves a label from place to place, said suction device having an interior chamber, a conduit leading from said chamber, and a suction device for establishing a subatmospheric pressure in said conduit, said suction device comprising a cylinder closed at one end by a head and open at its other end, a trunk piston slidable in the cylinder, the piston rod extending out through the open end of the cylinder, a pivot element connecting the free end of the piston rod to a fixed part, the cylinder being free to rock about the axis of said pivot element, an eccentric device connected to the cylinder head and operative to slide the cylinder relative to the piston while rocking the cylinder about said pivot element, a part carried by the cylinder and which has within it a passage which is always connected at an intermediate point with the interior of the cylinder and at one end to said conduit, the opposite end of said passage opening to the atmosphere but being normally closed by a valve, a lever, carried by the cylinder, on which the valve is mounted, and a part engageable by

21

said lever, as the cylinder rocks, thereby to swing the lever and open the valve.

47. In a labeling machine, in combination, a transfer carrier movable along a rectilinear, horizontal path toward and from a labeling station, a picker movable back and forth to and from a magazine along a path which intersects that of the carrier, means for moving the picker and to cause it to dwell at a transfer station, the carrier registering with the picker at the transfer station when the carrier is at one terminus of its path and having its label-engaging face parallel to and in transfer relation to the label-engaging surface of the dwelling picker, means to cause the label to adhere preferentially to the carrier, means for moving the carrier toward the labeling station while the picker continues to dwell at the transfer station thereby to slide the label from off the picker, and means to apply gum to the picker while it dwells at the transfer station.

48. In a labeling machine, in combination, a transfer carrier movable along a horizontal, rectilinear path toward and from a labeling station, a picker movable back and forth to and from a magazine along a rectilinear path which intersects that of the carrier, means for moving the picker and to cause it to dwell at a transfer station, the carrier registering with the picker at the transfer station when the carrier is at one terminus of its path and having its label-en-

30

22

gaging face parallel to and in transfer relation to the label-engaging surface of the dwelling picker, means to cause the label to adhere preferentially to the carrier, means for moving the carrier toward the labeling station while the picker continues to dwell at the transfer station thereby to slide the label from off the picker, a gum-transfer element which moves bodily with the carrier, and means for supplying gum to the transfer element, the transfer element moving with the carrier as the latter starts toward the labeling station and applying gum to the picker as the surface of the latter is bared by removal of the label.
